HOLLOW WALL STRUCTURE

George W. Williams, Burlingame, Calif.

Application June 11, 1938, Serial No. 213,218

8 Claims. (Cl. 72—48)

My invention relates to improvements in a hollow wall structure, and it consists of the combinations, constructions and arrangements hereinafter described and claimed.

6 An object of my invention is to provide an improvement over the forms of my invention shown in my Patents Nos. 1,826,111, issued October 6, 1931, and 1,887,668, issued November 15, 1932. In the patented devices, I show wall

10 forms of different shapes and these forms extend from the top plate to the bottom plate of a wall frame. The forms have inclined portions that extend inwardly and cooperate with other inclined portions for forming recesses that 15 will receive concrete. The concrete in the recesses forms concrete columns for the walls and the forms themselves are provided with paper backing for forming voids or hollow spaces in the wall.

20 In the present invention, I provide a form that has portions bent at right-angles and these portions extend transversely from one face of the wall to the other, to form recesses that will receive concrete. The adjacent forms are spaced 25 the desired distance apart to provide the desired width for the recesses. In this way, the size of the concrete columns can be regulated. The material forming the forms may be a wire mesh or a metal lath or even Celotex. In the case 30 of a wire mesh, a paper backing is used for preventing the entrance of concrete into the forms, except for the recesses which are designed to receive the concrete. With some types of metal laths, it is not necessary to use a paper backing.

35 The forms when in place, support the cement that is applied to the faces of the forms and the two layers of cement at opposite sides of the wall are integrally connected with each other by the cement columns. The result is a hollow 40 concrete wall construction which is homogeneous.

45 Other objects and advantages will appear in the following specification, and the novel features of the device will be particularly pointed out in the appended claims.

50 My invention is illustrated in the accompanying drawings forming a part of this application, in which

Figure 1 is a horizontal section through a wall showing one type of form and hollow wall construction;

Figure 2 is a side elevation of Figure 1 with the concrete facing removed as indicated by the line 2—2 of Figure 1;

Figure 3 is a section along the line 3—3 of

55 Figure 2;

Figures 4, 5, 6 and 7 are horizontal sections through modified forms of the device;

Figures 8 and 9 are vertical sections through modified forms of a hollow wall construction; and

Figure 10 is a horizontal section through another modified wall form.

In carrying out my invention, I make use of a wall frame having an upper plate 1 and a lower plate 2, see Figures 2 and 3. Wall forms 10 A are placed between the plates 1 and 2 and each wall form consists of two halves 3 and 4. The half 3 has a portion 5 bent at right-angles to the face 6 and a flange 7 extends at right-angles to the transverse portion. The other half 15 4 has a transverse portion 8 and a flange 9 similar to the portions 5 and 7. The two halves are placed against each other to provide a hollow space 10 and each half may be lined with paper on its inner surface so that the hollow 20 space 10 will have a layer of paper on all sides. Figure 1 shows the face 6 and the transverse portion 5 backed with a layer of paper 11 while the face of the half 4 and the transverse portion 8 is lined with paper 12. Should the material from which the halves 3 and 4 are constructed, be of a non-perforated type, such as Celotex and a certain type of metal lath, then the paper backing could be dispensed with. In the form shown in Figure 1, the flanges 7 and 25 9 and portions 13 and 14 are not provided with paper backing and this will permit concrete to pass through these portions since they are preferably of the wire mesh or perforated type.

The wall is constructed from a plurality of 30 these forms A placed adjacent to each other so that the transverse portion 5 of one form will be spaced the desired distance away from the transverse portion 8 of the adjacent form. The portions 5 and 8 together with the flanges 7 40 and 9 form the side walls for a concrete column. If desired, reinforcing rods 15 may be placed within the four walls and then the concrete may be poured around the reinforcing rods. When the concrete sets, the wall will be provided with 45 reinforced concrete columns 16. The flanges 7 and 9 and the portions 13 and 14 overlap the adjacent form a slight distance and act as a connecting link between the forms.

The mid portions of the forms may be braced by 50 a reinforcing member 17 that extends between the forms. The outer surfaces of the wall forms are covered with a layer of concrete and the two layers are shown at 18 and 19. This concrete will be integral with the concrete columns 16, since the 55

flanges 7 and 9 and portions 13 and 14 are not provided with a paper backing, and therefore the concrete will pass through the wire mesh or through the perforations in the metal lath and will join the layers 18 and 19 to the column 16. In this way, a homogeneous wall construction is provided. The spaces 10 form hollow portions in the concrete wall.

In Figures 2 and 3, I show a plurality of the forms A disposed one above the other and overlapping as at 20. The forms A may be continuous in height from the top plate 1 to the bottom plate 2 of the wall frame, or a number of forms may be superimposed one above the other. When the forms are superimposed as shown in Figures 2 and 3, they are each individually connected to the reinforcing members 17 by any suitable means such as by wires 21. The paper backing does not extend down through the overlapped portions of the forms and this will permit the overlapped portions to be interconnected by the concrete.

In Figures 4 to 7 inclusive, I show slightly modified forms of the invention. In Figure 4, the form B has two halves 22 and 23 that are provided with angularly-shaped recesses 24 and 25 disposed between the ends 26 of the form. The angular portions 24 and 25 mesh with each other at 27 and 28 to provide a concrete reinforcing member 29 of the shape shown. The form B has a paper backing 30 that also extends along the inclined portions to the points 27 and 28. The part 29 of the form is not provided with paper backing and therefore concrete will pass through this portion. The angular recesses 24 and 25 receive concrete that forms a concrete column 31 of the shape shown in Figure 4. The outer surfaces of the forms are covered with layers of concrete 32 and 33 and these are interconnected by the column 31. If desired, reinforcing members 34 and 35 may be placed across the entrance to the V-shaped portions 24 and 25. The members 34 and 35 will be embedded in the concrete.

In Figure 5 I show another modified form of the device. The form C is composed of two halves 36 and 37. The half 36 has an inclined portion 38 and a portion 39 which parallels the face 40. The half 37 has an inclined portion 41 and a flange 42 that extends at right-angles to the face 43 and at an acute angle to the inclined portion 41. The halves 36 and 37 are arranged in the manner shown and provide recesses for receiving concrete and in this way a concrete column 44 is formed in the wall. In actual practice, the two halves 36 and 37 are identical to each other, each having an inclined portion 38 at one end and an inclined portion 41 at the other. The portions 39 will contact with each other when the halves are assembled and the inclined portions 41 will contact with the portions 39. A paper backing 45 extends along the sides of the inner faces 40 and 43 and along the inclined portions 38 and 41. The portions 39 and the flanges 42 are not provided with paper backing and therefore the concrete will pass therethrough. The concrete columns 44 may be reinforced as at 46, if desired. The forms C will provide a hollow wall construction in which the layers of concrete 47 and 48 will be interconnected by the concrete columns.

Still another modified form is shown in Figure 6. The form D comprises two halves 49 and 50 that have transverse portions 51 and 52 extending at right-angles to the faces 53 and 54. Flanges 55 and 56 extend at an angle from the portions 51 and 52 for cooperating with similar flanges on the adjacent form for providing a reinforcing

mesh for a concrete column 57 that is positioned between the forms. The halves 49 and 50 are provided with paper backing 58 that extends along the faces 53 and 54 and along the portions 51 and 52. The flanges 55 and 56 are not provided with paper and this permits the concrete column 57 to connect the concrete layer 59 with a concrete layer 60.

The final form is shown in Figure 7. The form E shown in this figure, comprises two halves 61 and 62 carrying flanges 63 and 64 at their ends. The flanges overlap in the manner shown and the forms E are spaced apart to provide a place for a concrete column 65. The halves 61 and 62 have their inner surfaces lined with a paper 15 backing 66 and this paper backing extends along the inner flange. Hollow spaces 67 are thus provided in the wall by the forms and the concrete layers 68 and 69 are connected together by the concrete column 65. If desired, reinforcing rods 20 may be placed in the concrete column.

The forms disposed adjacent to the top and bottom rails are secured to the rails and their transverse portions are cut so as to clear the rails. This will permit the transverse portions to extend across the width of the wall.

It is possible to space the forms A further apart to provide concrete columns of greater width. This will permit the columns to be spaced a greater distance apart. The forms A will therefore be longer and additional reinforcing members 17 may be placed in the hollow space 10 to give the parallel sides of the form the necessary support.

In actual construction of the hollow wall shown in Figure 1, the reinforcing members 17 may first be placed in position and then the wiring and plumbing may be completed before the forms A are secured to the members 17 by wires 21. After the forms are secured in place, the concrete can be applied and form the concrete columns 16 and the outer layers of concrete 18 and 19.

In Figure 8 I show a vertical section through a hollow wall construction showing the concrete column in section. In this wall construction, metal plates 71 and 72 are used in place of the wooden rails 1 and 2. The plate 71 rests upon a concrete foundation 73 and dowels 74 project upwardly from the foundation and extend through openings in the bottom rail. The top plate 72 is initially supported by light metal studs 75 (see Figure 9) that take the place of the reinforcing members 17. The concrete column hides the stud in Figure 8. The forms A' are now secured to the studs 75 by wires 76 and the forms may extend throughout the height of the wall as shown, if desired. It is obvious that the forms A instead of the forms A' could be secured to the studs 75 if desired, these forms being superimposed above each other in the manner shown in Figures 2 and 3.

Concrete outer layers 77 and 78 are now applied to the outer surfaces of the forms A' and the concrete will form the concrete column shown at 79. Before the concrete is applied, reinforcing rods 80 may be secured to the dowels 74 and these rods will project through openings in the top plate 72 and will extend above the plate. A form (not shown) is used to form a concrete beam 81 on top of the plate 72. This concrete beam will be integrally connected to the hollow wall and the reinforcing rods 80 will extend into the bottom of the beam.

In Figure 9 I show a slightly different form of hollow wall construction. The forms A' have 77

their ends bent inwardly at 82 at a point beneath the top rail 12. The forming of the concrete beam 81 will therefore embed the top rail 12 since the concrete will extend down to the inwardly bent portions 82. The portions 82 are backed with paper 82' and this will prevent the concrete from dropping into the hollow space 83 which is similar to the space 10 in Figure 1. In all other respects this form of the invention 10 is the same as that shown in Figure 8 and therefore corresponding reference numerals will be given.

It is possible in the use of Celotex or similar material, to reinforce the material. In Figure 15 10 I show forms F formed of reinforced Celotex. Each form comprises two halves and the half 84 has a Celotex wall 85 reinforced at 86, and this wall is bent at 87 to extend transversely across the width of the hollow wall. The reinforcing 20 material extends beyond the transverse portion 87 and is bent at right-angles thereto as shown at 88. The other half of the form is shown at 89 and this half has reinforcing material 90 therein that extends beyond the Celotex as at 25 91 and parallels the portion 88. The forms when in position will provide hollow spaces 92 and the portions 88 and 91 will permit the concrete to pass into the space 93 provided between the transverse portions 87 and this concrete will form 30 a concrete column 93'. The outer surfaces of the forms may have layers of concrete 94 and 95 applied thereto and these layers will contact with the concrete column to form a homogeneous concrete wall with sound deadening and insulation 35 material comprising a part of the form. In actual practice, each half form 84 or 89 has a transverse portion 87 with the flange 88 at one end and the reinforcing material 91 extending beyond the Celotex at the opposite end. Both 40 form halves will therefore be identical.

While I have shown only the preferred forms of my invention it should be understood that various changes or modifications may be made within the scope of the appended claims without departing from the spirit of the invention.

I claim:

1. A hollow concrete wall construction comprising top and bottom plates, forms secured to the plates and having portions paralleling the 50 sides of the plates and transverse portions extending across the width of the plates with flanges that abut adjacent forms, the transverse portions and flanges providing concrete receiving enclosures, concrete poured into the enclosures for providing concrete columns, a layer of concrete inclosing the outer surfaces of said forms, the flanges having openings therein for permitting the concrete in the layers to bond with the concrete in the columns and provide a homogeneous wall, the other portions of the forms 55 being impervious to the concrete, whereby the forms will provide hollow spaces in the completed wall.

2. A hollow concrete wall comprising a plurality of wall forms, each form consisting of 60 two identical halves, each half having a face portion, a transverse portion, and a flange, the two halves of each form being assembled so that the flange and transverse portions are at opposite ends of the form and the face portion of each half contacts with the flange of the other half, thereby providing a hollow space in each form, the transverse portions of adjacent forms being spaced apart and the flanges of adjacent 65 forms cooperating with the transverse portions

for providing concrete-receiving enclosures, and concrete poured into the enclosures and constituting concrete columns when set.

3. A wall form comprising two identical halves, 5 each half having a flat surface with a V-shaped recess therein, the flat surfaces of the halves being arranged in parallel relation with the V-shaped recesses disposed opposite each other so that the apexes of the recesses interlock and a paper backing covering the inner sides of the 10 flat surfaces and the wall portions of the V-shaped recesses up to the point where they interlock.

4. A hollow wall comprising a plurality of forms, each having two identical halves, each 15 half having a flat surface with a V-shaped recess therein, the flat surfaces of the halves being arranged in parallel relation with the V-shaped recesses disposed opposite each other so that the apexes of the recesses interlock, a paper backing 20 covering the inner sides of the flat surfaces and the wall portions of the V-shaped recesses up to the point where they interlock, a layer of concrete covering each outer face of the forms and filling the recesses and the interlocked portions, 25 whereby concrete columns are provided that interconnect the layers of concrete and provide a homogeneous wall.

5. A wall form comprising two identical halves, 30 each having a flat surface with transverse portions extending at right-angles thereto, the halves in each form being arranged so that the transverse portions telescope with each other and provide box-like hollow spaces, adjacent forms 35 being spaced from each other for permitting concrete to be received in the space between the transverse portions.

6. A hollow concrete wall construction comprising top and bottom plates, reinforcing and form supporting members secured to the plates, 40 forms secured to the members and comprising two halves that have portions paralleling the sides of the plates and transverse portions that extend across the width of the plates, flanges carried by the transverse portions and contacting 45 with adjacent forms, said forms being spaced for spacing the transverse portions of adjacent forms the desired distance apart to provide concrete-receiving enclosures, concrete filling the space provided by the enclosures and constituting 50 concrete columns when set, and concrete covering the outer surfaces of the forms and bonding with the concrete columns to provide a homogeneous wall.

7. A hollow wall construction comprising a 55 foundation, a plate carried thereby, studs supported by the plate, a top plate resting on the top of the studs, forms secured to the studs and having their upper ends bent inwardly to underlie the top plate and be spaced therefrom, a concrete beam embedding the top plate and extending to the inwardly bent portions, concrete layers covering the forms and being integral with the top beam and foundation, and concrete columns extending between the plates and being integral 60 with the concrete layers.

8. In a hollow wall construction, vertical reinforcing members extending throughout the height of the wall, wall forms secured to the reinforcing members, each wall form comprising 70 two identical halves with portions defining the two sides of the wall and transverse portions extending across the width of the wall, flanges carried by the transverse portions and paralleling the side wall portions, the two halves of each 75

form being so arranged as to dispose the transverse portions at opposite ends of the form, the adjacent forms being disposed along the wall so that the transverse portions of adjacent forms ⁵ will be spaced from one another and the flanges will cooperate with the transverse portions to

provide concrete-receiving enclosures extending vertically throughout the height of the wall, whereby the concrete may be poured into the tops of the enclosures and when set will provide concrete columns.

GEORGE W. WILLIAMS. ⁵
